UNITED STATES PATENT OFFICE.

MARTIN PRIOR BOSS, OF SAN FRANCISCO, CALIFORNIA.

BOILER.

SPECIFICATION forming part of Letters Patent No. 684,598, dated October 15, 1901.

Application filed February 2, 1901. Serial No. 45,734. (No model.)

To all whom it may concern:

Be it known that I, MARTIN PRIOR BOSS, a citizen of the United States, residing in the city and county of San Francisco and State of California, have invented certain new and useful Improvements in Boilers; and I do hereby declare the following to be a full, clear, and exact description of the same.

My invention relates to that class of boilers known as "vertical water-tube boilers."

The object of my invention is to provide efficient circulation and of such a nature that the feed-water injected thereto is at once thoroughly heated and the salts and sediment are well precipitated before the water reaches the tubes.

These ends are attained by the construction and relative disposition of parts, which I shall now fully describe by reference to the accompanying drawings, in which—

Figure 1 is a vertical front elevation of the boiler with its setting-walls in section. Fig. 2 is a side elevation of same. Fig. 3 is a top plan. 25 A is a vertical cylinder or drum having projecting from and communicating with it above and below the horizontal boxes or chambers B B', between which extend the vertical tubes C, which are exposed to the fire from 30 one or more sides. The boiler-setting may be so arranged as to have the fire near the lower portion of the tubes and extend upwardly, or, as here shown, the preferable form is to have the fire near the upper portion 35 of tubes and extend downwardly. Accordingly the setting D is so made as to have the fire-chamber E about the upper portion of the tubes, and thence the setting-walls extend downwardly, forming a flue, preferably 40 a zigzag one e, about the lower portion of the tubes, terminating in a bottom flue e' sufficiently capacious for the draft, said bottom flue communicating with the exit-flue F. In 45 order to increase the area at the water-line, there is an exterior drum G, preferably horizontally disposed at one side of the upper portion of the drum A, and said drum G is connected with drum A by the upper and lower elbows g g'. The drum G may thus 50 serve also as a steam-drum. The drum A is best extended some distance below the lower

horizontal box B' to serve as a sediment-depository from which the deposited material may be blown out at a. There are additional blow-offs b at the outer end of the lower box 55 B'. In operation a strong up-current is engendered in the vertical tubes C, which induces a down-current in the vertical drum A, thus giving a regular circulation. The feed-water being injected into the vertical column 60 is at once thoroughly heated, and the salts and sediment are well precipitated out of it before it reaches the tubes.

Having thus described my invention, what I claim as new, and desire to secure by Letters 65 Patent, is—

1. A boiler consisting of a vertical drum or cylinder, a horizontal box or chamber communicating with said vertical drum or cylinder, a second horizontal box or chamber communicating with said drum, and vertical water-tubes connecting said horizontal boxes or chambers. 70

2. A boiler consisting of a vertical drum or cylinder, a horizontal box or chamber communicating with the vertical drum or cylinder, near its upper end, a second horizontal box or chamber communicating with the vertical drum or cylinder far enough above its lower end to form said extended lower end 75 of the drum or cylinder into a sediment-depository, and vertical water-tubes connecting the two horizontal boxes or chambers. 80

3. A boiler consisting of a vertical drum or cylinder, a horizontal box or chamber communicating with said vertical drum or cylinder, a second horizontal box or chamber communicating with said drum, vertical water-tubes connecting said horizontal boxes or chambers, and an exterior drum connected 85 with the upper portion of the vertical drum or cylinder and so disposed as to increase the area of the water-line. 90

4. A boiler consisting of a vertical drum or cylinder, a horizontal box or chamber communicating with said vertical drum or cylinder, a second horizontal box or chamber communicating with said drum, vertical water-tubes connecting said horizontal boxes or chambers, and a horizontal exterior drum, 95 having an upper and lower connection with the upper portion of the vertical drum or 100

cylinder, and so disposed as to increase the area of the water-line and serve also as a steam-drum.

5. A boiler consisting of a vertical drum or cylinder, a horizontal box or chamber communicating with said vertical drum or cylinder, a second horizontal box or chamber communicating with said drum, vertical water-tubes connecting said horizontal boxes or chambers, and a setting comprising a fire-chamber in which said vertical water-tubes are exposed to the fire for a portion of their length, and a flue from the fire-chamber in which the remaining length of said tubes are 15 exposed to the flames.

6. A boiler consisting of a vertical drum or cylinder, a horizontal box or chamber communicating with said vertical drum or cylinder, a second horizontal box or chamber communicating with said drum, vertical water-tubes connecting said horizontal boxes or chambers, and a setting comprising a fire-chamber in which the upper portion of the tubes are exposed to the fire, and a flue from 25 said fire-chamber to carry the flames downwardly around the lower portion of the tubes.

7. A boiler consisting of a vertical drum or cylinder, a horizontal box or chamber communicating with said vertical drum or cylinder, a second horizontal box or chamber com- 30

municating with said drum, vertical water-tubes connecting said horizontal boxes or chambers, and a setting comprising a fire-chamber in which the upper portion of the tubes are exposed to the fire, a downward zigzag flue, to carry the flames downward about the lower portion of the tubes, and a bottom flue communicating with the zigzag flue and leading to an exit. 35

8. A boiler consisting of a vertical drum or cylinder, a horizontal box or chamber communicating with said vertical drum or cylinder, a second horizontal box or chamber communicating with said drum, vertical water-tubes connecting said horizontal boxes or 40 chambers, an exterior drum connected with and so disposed with relation to the vertical drum or cylinder as to increase the area of the water-line, and a setting comprising a fire-chamber in which the upper portion of the tubes are exposed to the fire and a downward flue from the fire-chamber to carry the flames down about the lower portion of the tubes and thence to an exit. 45

In witness whereof I have hereunto set my hand. 50

MARTIN PRIOR BOSS.
